UNITED STATES PATENT OFFICE.

CHARLES U. CARPENTER, OF DAYTON, OHIO.

TYPEWRITING MACHINE.

Application filed May 3, 1922. Serial No. 558,052.

To all whom it may concern:

Be it known that I, CHARLES U. CARPENTER, a citizen of the United States, residing at Dayton, in the county of Montgomery and

5 State of Ohio, have invented certain new and useful Improvements in Typewriting Machines, of which the following is a specification.

My present invention relates primarily to 10 the type-bars and means for operating the same, and the relations between the operating means and the type-bars, and has for its object the provision of novel arrangements of type-bars and operating means for the 15 same, whereby simplicity and ease of operation is obtained, and compactness is assured, for providing a typewriter of low structure and short depth from front to rear, and wherein extreme visibility of the writing is 20 obtained.

It is the object of my invention, further, to in novel manner provide type-levers having low pivots and key-levers for operating the same having pivots in advance of the 25 pivots of the type-levers; further, to provide key-levers located wholly in advance of the pivots for the type-levers; further, to arrange the pivots of the collective type-levers on an arc arranged with an upward and 30 rearward inclination, and, further, with such arrangement, to provide resting means for the type-ends of the type-levers arranged on substantially an arc of less curvature in a substantially horizontal plane, 35 whereby a low structure and a compact arrangement are obtained.

It is the object of my invention, further, to arrange the key-levers into a plurality of series each of which comprises a number of 40 key-levers, and to provide coincident pivotal axes for the key-levers of each series; and, further, to vary the lengths of the work-arms of the key-levers to equalize the strokes of their power or key ends.

45 It is the object of my invention, further, to provide novel pivoting arrangement for the type-levers whereby the types print upon an upper sector of the platen; further, to provide a type-lever and a key-lever and link 50 for operating the same, the pivot of the type-lever being lower than the pivot of the key-lever in novel manner; further, to provide a curved type-bar, and a key-lever for operating the same the pivoting means for which 55 latter extends within the concavity of the curvature; further, to provide novel pivoted

type-bars, and key-levers for operating the same having pivoting means adjacent to the type-ends of the type-bars when in retracted positions.

It is the object of my invention, further, to arrange the key-levers with their keys in a plurality of banks, exemplified as four banks, and pivoting means for the key-levers located between the key-ends of the key-levers and the type-levers; further, to provide spaced-apart pivoting means for key-levers of different banks, and type-bars whose type-ends are normally located between the pivoting means of the respective banks; and, further, to provide novel means whereby the type-end of the type-bar has a long sweep of movement imparted thereto by novel means, whereby accelerating motion is imparted to the type-end of the type-bar for causing the striking of the type with a sharp blow to effect sharp outlining and legibility in the printing of the same, the latter portion of the stroke being aided by gravity.

The invention will be further readily understood from the following description and claims, and from the drawings, in which latter:

Fig. 1 is a plan view of so much of a typewriting machine as is necessary to illustrate my invention.

Fig. 2 is a central vertical cross-section of the same, the section being taken on a line corresponding to the line 2-2 of Fig. 1, and parts of the operating mechanism being broken away, the key-lever of the lower bank of keys and the type-bar with which the same connects being shown in retracted position in full lines and in operated position in dotted lines.

Fig. 3 is a similar view showing the key-lever of the second bank of keys and the type-bar with which it connects in retracted position in full lines and in operated position in dotted lines.

Fig. 4 is a similar view showing the key-lever of the third bank of keys and the type-bar with which it connects in retracted position in full lines and in operated position in dotted lines.

Fig. 5 is a similar view showing the key-lever of the fourth bank of keys and the type-bar with which it connects in retracted position in full lines and in operated position in dotted lines.

Fig. 6 is a front elevation of the same, partly broken away.

Fig. 7 is a vertical cross-section of the same, taken on the line 7—7 of Fig. 1; and

Fig. 8 is a cross-sectional detail of the pivoting means for the type-levers, taken 5 on the line 8—8 of Fig. 7.

The frame of the machine is indicated at 11, and may be of suitable construction to support the operating parts, which, it will be noted, are all located in compact arrangement so as to provide a low machine which 10 will occupy little space, the parts being also arranged as to be extremely compact from front to rear so that the dimensions of the machine shall be small in all directions for 15 providing extreme compactness and portability of the machine.

Type-bars 12 are provided, shown as levers, several of which are shown. These 20 type-bars operate in slots 13 of a support 14 in the frame, and swing on pivots, received through the pivot-ends of the type-bars, and located in wings 16, formed by 25 said slots. The pivot-ends of said type-bars are shown formed as discs 17, guided by the walls of said slots, for insuring accuracy in the movements of the type-bars.

The support 14 is shown as an arc-piece at the bottom of the frame and provides means for pivoting the type-levers at the 30 bottom of the machine. It is exemplified secured by means of screws 18 to an upwardly and rearwardly slanting plate 19 which is in turn secured to the sides of the main frame. The wings 16 extend at an 35 acute angle from the horizontal plane of the bottom of the frame for ease and range of movement of the type-levers. The arc-piece has a rearward and upward inclination for so relatively placing the middle type-levers and the end type-levers that directness of stroke is obtained. The type-levers are shown pivoted on a pivot-rod 21, of 40 bow-form, located in a recess 22 in the arc-piece. The ends of the pivot-rod are 45 threaded and nuts 23 received thereover for drawing the pivot-rod in the direction of its length and firmly seating the pivot-rod in its arc-recess.

The constructions and arrangements of the 50 parts permit the arc-support to be placed in the lowermost part of the machine without working parts therebelow. The working parts which extend from front to rear may be located at the sides of the arc-support, exemplified by the location of the links 55 for shifting the carriage hereinafter referred to. It will be noted that the key-levers are located wholly in front of the arc-piece, providing a machine which is short and compact from front to rear.

Each of the type-bars has suitable types 25, 26, thereon, shown located on a head 27, suitably fixed to the swinging end of the type-bar. The type-ends of the type-bars 30 normally rest in retracted positions on a

pad 28, located on a shelf 29, suitably secured in the frame.

The shelf 29 is shown arranged on a substantial arc of less curvature than the curvature of the arc-piece 14. The shelf is also 70 preferably located in a substantially horizontal plane. This permits all of the type-ends of the type-levers to lie low in retracted positions, and results in a low structure of typewriting machine. The shank 35 of the 75 type-bar is shown curved upwardly when in retracted position, for providing a space in the concavity of the curvature in which pivoting means for key-levers may be located. The curved form of the type-bars enables 80 additional compactness of arrangement to be obtained, and aids in presenting the type for easy access by the operator when in retracted position, as for cleaning and inspection, and for the striking the type upon the 85 paper, which is received about the platen-cylinder 37, preferably at a point above the horizontal plane in which the axis of rotation of said cylinder is located, whereby extreme visibility of the writing is obtained. 90

The paper being typewritten is arranged to be received about the platen and to be held thereagainst by paper guides 38 of suitable construction, to cause contact between the paper and the cylinder upon the upwardly 95 and rearwardly extending sector 39 of said cylinder, along which the writing takes place to present the writing upwardly and forwardly for ready view by the operator.

The platen is arranged to be raised and 100 lowered by suitable mechanism and to travel crosswise of the type in any ordinary manner.

The raising and lowering means is exemplified as comprising bell-crank levers 41, 105 42, pivoted to the main frame at the rear of the latter, shifting levers 43, 44, pivoted to the front part of the main frame, and links 45, 46, articulated to said respective levers by rear articulations 47 and front articulations 48, the links passing the arc-support 110 for the type-levers at the sides of the latter.

Key-levers are provided for operating the type-bars, the key-levers being exemplified 115 as wholly in advance of the type-bars. These key-levers are preferably arranged in a plurality of banks, exemplified as four banks 51, 52, 53, 54, of keys. The key-board may represent a standard key-board. The 120 key-levers of the respective banks are shown at 56, 57, 58, 59. The key-levers are preferably arranged into a plurality of series or sets, each series or set comprising a plurality of key-levers having coincident axes. 125

I shall first describe the operative connections of the key-levers 58, 59, (see Figs. 4 and 5), and shall then describe the operating connections of the key-levers 56, 57, (see Figs. 2 and 3), whose pivoting means are 130

differently located forwardly of the pivoting means of the key-levers 58, 59. If desired, the key-levers may have their pivotal axes coincident, or otherwise arranged within the 5 scope of the appended claims.

The type-levers are pivoted adjacent to the bottom of the frame, and the key-levers are preferably pivoted above the pivots of the type-levers, for providing ease of operation 10 and wide range of movement of the type-ends of the type-levers by simple mechanism.

The key-levers 58, 59, are shown of bell-crank form, respectively pivoted in their angles by pivot-bearings 60 and 61 about a 15 pivot-rod 62, suitably supported in the frame of the machine. These pivot-bearings and the pivot-rod are shown located below the type-ends of the type-bars, and as extending within the concavity of the curved shanks of 20 the type-bars when in retracted positions. The key-levers 58, 59, comprise key-arms 64, 65, which extend forwardly, and on the forward ends of which the keys 53, 54, are respectively located, the said key-levers also 25 having arms 66, 67, which extend downwardly and with which links 68, 69, are respectively articulated at 71, 72, the rear ends of the links being articulated with the type-bars by articulations 73, 74. Springs 75, 76 30 between the respective arms 66, 67 and the frame of the machine normally retract the key-levers and the type-bars.

The key-arms may be designated the power-arms of said key-levers, and the arms 35 66, 67 the work-arms thereof. Referring to Figs. 4 and 5, it will be noted that the power-arm of the key-lever 58 is longer than the power-arm of the key-lever 59, the work-arm of the key-lever 58 being also longer than 40 the work-arm of the key-lever 59, in order to equalize the power required to operate the respective levers.

Referring to Figs. 4 and 5, when the keys of the respective key-levers 58, 59 are struck, 45 the said key-levers and links, and the type-bars connected therewith, move from the positions shown respectively in Figs. 4 and 5 in full lines, to the positions shown in said figures in dotted lines, these movements being accelerating movements during their progress, and the movements being accomplished easily by striking pressure of the fingers, for the reason that the articulations 73, 74, between the links and the type-bars 50 move through their arcs of movements with the least resistance with relation to the power applied, the latter part of these movements being aided by the gravity of the descending type-lever, the result being quick, 55 sharp blows by the type upon the paper being printed, for producing well-defined impressions and capacity for a maximum number of carbon copies.

The pivot-shaft or rod 62 for the key-levers 58, 59, is located in rear of the type-

ends of the type-bars and lower than said type-ends, whereby compactness is produced.

The key-levers 56, 57, (see Figs. 2 and 3), may, if desired, have their pivots upon the pivot-rod 62. I have, however, shown the 70 same pivoted on a pivot-rod 81, suitably supported by the frame of the machine, and located in close adjacency to the type-ends of the type-bars, and preferably nearer the keys than the pivot-rod 62, so as to reduce 75 the lengths of the power ends of said levers, thereby aiding in equalizing the strokes upon the keys of all the banks of keys. Equalizing said strokes is also accomplished by varying the lengths of the rear arms of 80 the key-levers 56, 57.

The key-levers 56, 57, preferably respectively comprise the arms 82, 83, which are the power-arms of said levers, at the forward ends of which the keys are located, 85 and arms 84, 85, which are the work-arms of said levers, which extend downwardly, and have articulations 86, 87, with links 88, 89, which in turn have articulations 90, 91, with the type-bars. Springs 92, 93, between the 90 arms 84, 85, and the frame, normally retract the key-levers 56, 57, and the type-bars having operative connection therewith. For aiding in the pivoting of said key-levers 56, 57, and arranging the key-levers in a non-interfering relation, I prefer to merge the respective arms thereof into upwardly extending arms 94, 95, the upper ends of which have bearings 96, 97, about the pivot-rod 81.

The arrangement of these key-levers 56, 100 57, and their links and connections with the type-bars, are, as in the case of the key-levers 58, 59, such as to cause an accelerating movement of the type-bars in manner hereinbefore explained, aided by gravity, 105 for effecting sharp blows of the type upon the paper to produce well-defined impressions and capacity for a number of clear carbon copies.

The key-arms of the key-levers may be 110 received through suitable slots 98 in a front plate or comb 99 in the frame. Placing the key-levers on a plurality of rods or shafts enables wide pivot-bearings to be provided for said levers, to prevent lateral movements 115 of said levers and to maintain said levers in their proper paths of movement. The pivot-bearings of the key-levers on each of said shafts are in the planes of the key-levers on the other of said shafts.

My improved construction and arrangement of parts provides low visibility of the printing lines presented in an upward forward direction for ready viewing by the operator. The type-bars are provided with 125 curved shanks for aiding in compactness of arrangement; the key-levers and the operative connections between the same and the type-bars are located in front of the type-bars and below the upper ends thereof, and 130

my improved construction enables short key-levers to be employed, producing compactness of parts, quick blows of the type-bars, and permitting rapid operation of the machine.

My improved construction and arrangement further provides means whereby a wide range of movement is imparted to the type-end of the type-bar with a minimum movement of the key, due to the novel mounting of the key-lever and its connection with the type-bar. My improved construction further enables the operating parts to be located in close relation to produce a typewriter which is light in weight, and small and compact, and is especially adapted as a so-called portable typewriter.

It will be noted further that the pivot of the key-lever is adjacent to the type-end of the type-bar, and that the rear arm of the key-lever, the link and the type-bar have the general form of a triangle when in retracted position, this arrangement producing ease of operation.

Having thus fully described my invention, what I claim as new and desire to secure by Letters Patent, is:

1. In a typewriting machine, a key lever pivoted approximately at the top of the machine, and having one portion extended forwardly and another portion extending downwardly to approximately the bottom of the machine, a type bar pivoted near the bottom of the machine and extending upwardly to approximately the top thereof, and a link connecting the end of the key lever with the type bar.

2. In a typewriting machine, a bank of key levers pivoted approximately at the top of the machine, each having one portion extended rearwardly and another portion extending downwardly to approximately the bottom of the machine, a bank of type bars, a segmental pivot for the type bars near the bottom of the machine, said type bars extending upwardly to approximately the top of the machine, and links connecting the ends of the key levers with the type bars.

3. In a typewriting machine, a key-lever having an inwardly and upwardly extending portion, a vertical portion terminating in an eye, and a downwardly projecting portion connected to the base of the vertical portion, a type bar, and means for connecting the lower end of the downwardly projecting portion of the key lever adjacent the bottom of the machine with the base of the type-bar, said type-bar being pivoted near the bottom of the machine and extending upwardly to near its top.

4. In a typewriting machine, a key-lever extending inwardly to a pivot, a pivot, a portion of the key lever extending inwardly and downwardly from said pivot, a type-bar pivoted near the base of the machine and

having a plurality of types thereon, a link at the lower end of the last mentioned portion of the key lever directly connecting said key-lever to the type-bar, said type-bar extending to near the top of the machine, being adapted to move through an arc to engage with a platen, a platen, and means to move said platen vertically.

5. In a typewriting machine, a bank of key-levers each consisting of a substantially horizontal portion and a substantially vertical portion, each of said levers being pivoted at the point of juncture of the two portions, the last mentioned portion having its free end adjacent the bottom of the machine, a single link for each lever connected directly thereto and to a type bar and lying in a substantially horizontal position adjacent the bottom of the machine, and a bank of type-levers having their lower ends pivoted on a segment adjacent the bottom of the machine.

6. In a typewriting machine, a frame, a plurality of type-bars and angled key-levers arranged in banks, a portion of each key lever extending to the lower portion of the machine the type bars being pivoted in a semi-circular supporting segment located adjacent the bottom of said frame, said type-bars being at an angle to the bottom of the machine of about 45° when at rest, the lower ends of said key-levers being approximately at the same elevation as the pivoted ends of the type bars.

7. In a typewriting machine, a frame, a plurality of type bars having a plurality of types thereon and angled key-levers arranged in banks, a portion of each key lever extending to the lower portion of the machine and being connected to a type-bar, said type bars being pivoted in a semi-circular supporting member also located adjacent the bottom of said frame, said type-bars being at an angle to the bottom of the machine of about 45° when at rest, the lower ends of said key-levers being approximately at the same elevation as the pivoted ends of the type bars, a platen, means for elevating vertically said platen adapted to pass beneath said semi-circular supporting means and between it and the frame of the machine to a point adjacent the banks of keys.

8. In combination in a typewriting machine, a frame, a plurality of key-levers each of which consists of inwardly and downwardly extending portions pivoted at the junction of the two portions, rearwardly extending links connected to each of said lower ends of the downwardly extending portions of the key-levers and also connected to their respective type-bars, a semi-circular means located adjacent the bottom of said frame and a plurality of type-bars pivoted therein having their free ends adapted to move through an arc and a vertically movable platen for cooperating with the

- type bars for engaging the free ends of said type-bars.
9. In combination in a typewriting machine, a frame, a plurality of key-levers each of which consists of inwardly and downwardly extending portions pivoted at the junction of the two portions, rearwardly extending links connected to each of said lower ends of the downwardly extending portions of the key-levers and also connected to their respective type-bars, a semi-circular means located adjacent the bottom of said frame and a plurality of type-bars pivoted therein having their free ends adapted to move through an arc and a platen for engaging the free ends of said type-bar, said frame being so arranged that it protects and extends above the free ends of the type bars in their position of rest.
10. In combination in a typewriting machine, a frame, a plurality of key-levers each of which consists of inwardly and downwardly extending portions pivoted at the junction of the two portions, rearwardly extending links connected to each of said lower ends of the downwardly extending portions of the key-levers and also connected to their respective type-bars, a semi-circular means located adjacent the bottom of said frame and a plurality of type-bars pivoted therein having their free ends adapted to move through an arc and a platen for engaging the free ends of said type-bar, and means extending from a point adjacent the outer ends of the key-levers to said platen for controlling its elevation.
11. In a typewriting machine, a combination of a frame, a plurality of keys in a series of banks, each key having a lever extending inwardly to a pivot and another portion of the lever extending downwardly therefrom towards and adjacent to the bottom of the frame, a link connected to each key-bar extending rearwardly approximately in the horizontal at an angle to its type-bar to which it is connected, and a plurality of type-bars having their lower ends pivoted in a semi-circular supporting member adjacent the bottom of the machine and a platen co-operating with the type levers.
12. In combination in a typewriting machine of a frame, means to support a plurality of key-levers arranged in banks, each of said levers extending substantially inwardly and downwardly, type bars pivoted on a segmental member, the lower ends of some of said levers being located below the pivotal point of connection of the type-bars, and links connected to each key-bar at one end and at the other end to a point above the pivotal point of connection of the type-bars on the segmental member.
13. In combination in a typewriting machine of a frame, means to support a plurality of key-levers arranged in banks, each of said levers extending substantially inwardly and downwardly, type bars pivoted on a segmental member, the lower ends of some of said levers being located below the pivotal point of connection of the type-bars, and links connected to each key-bar at one end and at the other end to a point above the pivotal point of connection of the type-bars on the segmental member, the lower ends of some of said levers being located below the pivotal point of connection of the type-bars, and links connected to each key-bar at one end and at the other end to a point above the pivotal point of connection of the type-bars on the segmental member, a platen, and means extending from a point adjacent the keys to the platen for varying its elevation.
14. In a typewriting machine, a frame, key levers therein, means at the top of the frame to suspend the key levers pivotally, type bars, means adjacent the bottom of the machine to directly connect the inner ends of type-bars and key-levers, said connecting means being at an angle to the type-bars and key-levers when at rest, and segmental means to pivotally support the type-bars adjacent the bottom of the machine while the free ends thereof when at rest are located adjacent the key-bar suspending means.
15. In a typewriting machine, a frame, key levers therein, means at the top of the frame to suspend the key levers pivotally, type bars, means adjacent the bottom of the machine to directly connect the inner ends of type-bars and key-levers, said connecting means being at an angle to the type-bars and key-levers when at rest, and segmental means to pivotally support the type-bars adjacent the bottom of the machine while the free ends thereof when at rest are located adjacent the key-bar suspending means, and a platen at the rear of the frame located at substantially the same distance from the central type-bar pivots as the key-bar pivots are removed from the central type-bar pivots.
16. In a typewriting machine, a frame, a pair of spaced transverse shafts near the top and the front of the machine, a plurality of key-levers suspended therefrom, one series of said key-levers extending inwardly and downwardly having vertical portions supporting them pivotally on one of the shafts, the other series of key-levers consisting of inwardly and downwardly directed portions and pivoted on their shafts at the point of junction of the two portions.
17. In a typewriting machine, a frame, a pair of spaced transverse shafts near the top and the front of the machine, a plurality of key-levers suspended therefrom, one series of said key-levers extending inwardly and downwardly having vertical portions supporting them pivotally on one of the shafts, the other series of key-levers consisting of an inwardly and downwardly directed portion and pivoted on their shafts at the point of junction of the two portions, a semi-circular type-bar supporting element located at an angle to the vertical and inclined rearwardly and having pivotally mounted thereon a plurality of type-bars,

the pivotal points thereof being adjacent the bottom of the frame, said type-bars when at rest being inclined towards the forward portion of the machine at an angle to the vertical with the free ends thereof adjacent to the suspending shafts for the key-levers, a plurality of links respectively connecting the lower ends of the key-levers to the type-bars, the point of connection of 5 said links to the type-bars being above the pivotal point of connection of the type-bars on the semi-circular supporting member, and a platen on the rear of the frame so arranged that the type face of the type-bars 10 engage with the platen above its axis.

18. In a typewriting machine, a frame, a pair of spaced transverse shafts near the top and the front of the machine, a plurality of key-levers suspended therefrom, one series 15 of said key-levers extending inwardly and downwardly having vertical portions supporting them pivotally on one of the shafts, the other series of key-levers consisting of an inwardly and downwardly directed portion being pivoted on their shafts at the point of junction of the two portions, a semi-circular type-bar supporting element 20 located at an angle to the vertical and inclined rearwardly and having pivotally 25 mounted thereon a plurality of type-bars, the pivotal points being adjacent the bottom of the frame, said type-bars when at rest being inclined toward the forward portion of the machine at an angle to the vertical with the 30 free ends thereof adjacent to the suspend- 35

ing shafts for the key-levers, a plurality of links respectively connecting the lower ends of the key-levers to the type-bars, the point of connection of said links to the type-bars being above the pivotal point of connection 40 of the type-bars on the semi-circular supporting member, a platen on the rear of the frame so arranged that the type-ends of the type-bars engage with the platen above its axis, means extending from the front of the machine to the platen for changing the elevation of the platen and means on the ends 45 of the type-bars for mounting different type above the other for engagement with the platen, depending upon the height thereof. 50

19. In a typewriting machine, the combination of a curved type-bar and a key-lever having a pivot-bearing extending into the concavity of said curved type-bar when said type-bar is in retracted position. 55

20. In a typewriting machine, the combination of pivoted type-bars having rocking type-ends, and a plurality of key-levers arranged into a plurality of banks having spaced-apart pivots, the type-ends of said type-bars normally located in the space between said last-named pivots. 60

In testimony whereof, I have hereunto signed my name in the presence of two subscribing witnesses.

CHARLES U. CARPENTER.

In presence of—

J. A. DADSWELL,
FLOYD A. WOODS.
